EASEL

George C. Klick, Fort Lauderdale, Fla.

Application July 27, 1944, Serial No. 546,794

1 Claim. (Cl. 248—197)

My invention relates to improvements in easels, the primary object in view being to provide a simply constructed, collapsible support for holding screens and the like in elevated position and at selected levels for painting, and which is specially equipped for holding a paint bucket within convenient reach and in a manner such that the bucket cannot be easily upset.

Another object is to provide a device of the character above set forth which is strong, while at the same time light in weight and therefore easy to handle, and is inexpensive to manufacture.

Other and subordinate objects are also comprehended by my invention, all of which, together with the precise nature of my improvements, will be readily understood when the succeeding description and claim are read with reference to the drawings accompanying and forming part of this specification.

In said drawings:

Figure 1 is a view in perspective of my improved easel in a preferred embodiment thereof.

Figure 2 is a view in side elevation showing the easel collapsed, or folded.

Figure 3 is a view in horizontal section taken on the line 3—3 of Figure 1.

Reference being had to the drawings by numerals, and to the easel as illustrated, said easel comprises a pair of elongated, rectangular front and rear frames 1, 2, each comprising a pair of parallel upright bars 3 in the case of the front frame 1 and 4 in the case of the rear frame 2. The frames 1, 2 are swingably connected together at the upper ends thereof for folding and unfolding, with the upper ends of the bars 3 of the front frame 1 between the corresponding ends of the side bars 4 of the rear frame 2, and by means of a cross rod 5 suitably extended through said upper ends of said bars 3 and fixed in the upper ends of said bars 4. Cotter pins, as at 6, extended through the rod 5 prevent the upper ends of the side bars 3 from creeping inwardly along the cross rod 5. At a suitable distance from the lower ends of the side bars 3, a cross rod 7 connects said bars 3 together. A cross rod 8 similarly connects the side bars 4. A pair of diagonal crossed brace bars 9 connects the side bars 3 of the front frame 1 together above the cross rod 7. A similar pair of crossed brace bars 10 similarly connects the side bars 4 of the frame 2 together.

An elbow locking brace extends between the front and rear cross rods 7, 8, and which comprises a pair of front and rear bar sections 11, 12 hinged together, end to end, as at 13, for upward swinging into parallel relation and to break down-

wardly, the front section 11 being swingably mounted on the cross rod 7 between confining cotter pins, as at 14, and extending forwardly of said rod, and the rear section 12 being swingably mounted on the rod 8 between confining cotter pins 15. A bolt 16 and keeper 17 on said sections 11, 12 provide for locking the described brace in straightened out position to maintain the frames 1, 2 unfolded in spread-apart relation.

An annular flat support 18 for a paint bucket is suitably secured, as at 19, on top of the section 11 and a cross bar 20 forming part of said section and in front of the cross rod 7.

The side bars 3 of the front frame 1 are provided, above the support 18 with longitudinal openings 21 in the front edge thereof to receive nails, not shown, for supporting a screen, not shown, or similar article, thereon in elevated position for painting.

As will be readily understood, the described easel is unfolded for use by swinging the front and rear frames 1, 2 about the axis of the cross rod 5 into spread-apart relation, straightening out the elbow locking brace by swinging the sections 11, 12 upwardly into aligned relation and locking the same in such relation by means of the bolt 16 and keeper 17. In the locked condition of the locking brace, the support 18 is maintained in a horizontal position to seat a paint bucket, not shown, thereon for convenient access thereto in painting screens or the like mounted on the bars 3 in the manner already described. To fold or collapse the easel, it is merely necessary to unlock the bolt 16 and break the locking brace in a manner which will be understood so that the frames 1, 2 may be swung into a common plane, substantially. In this operation the support 18 is swung by the section 11 into substantially the same plane as the frames 1, 2 so that the easel is compactly folded or collapsed for storage or carrying.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claim.

What I claim is:

An easel for use in painting screens and the like comprising a pair of elongated frames having upper ends pivotally connected together for swinging of the frames into and from downwardly divergent relation, each frame comprising a

lower cross rod, and an elbow locking brace extending between said rods for maintaining the frames in said relation and comprising a pair of sections swingable on said rods and hinged together to break downwardly and thereby provide for swinging of the frames out of such relation, one of said sections having fixed thereon

a support for a paint bucket, said sections aligning in butt joint relation when swung outwardly to prevent the same from being swung upwardly out of aligned relation, and latching devices on said sections for retaining the same in aligned relation against breaking downwardly.

GEORGE C. KLICK.
